UNITED STATES PATENT OFFICE.

WILLIAM PAUL RUDKIN, OF OKLAHOMA CITY, OKLAHOMA.

LIQUID-FUEL BURNER.

Application filed September 23, 1924. Serial No. 739,320.

To all whom it may concern:

Be it known that I, WILLIAM P. RUDKIN, a citizen of the United States, residing at Oklahoma City, in the county of Oklahoma and State of Oklahoma, have invented certain new and useful Improvements in Liquid-Fuel Burners, of which the following is a specification.

This invention relates to a liquid fuel burner, and particularly to a construction adapted for burning low grade fuel oils for heating purposes.

In fuel burners the use of a low grade oil when confined and vaporized quickly clogs or chokes the burner, due to the presence of a large percentage of carbon content and the deposit of such carbon in the vaporizing of the oil at the time of ignition. Further it has been found desirable and more efficient to introduce the air necessary for proper combustion at a point above the heated liquid fuel so that it mixes with the gas or vapor rising therefrom and this mixture is utilized to heat the body of the fuel in the burner by means of heat conductors exposed to the flame and extending into the fuel body.

In usual constructions of fuel burners the heating capacity thereof is limited and I provide for a variation of such capacity by the use of independent conductor units through which the air is introduced to the fuel, and such a construction permits the use either of a liquid fuel or the introduction of a gaseous fuel, such as natural gas, into the fire box so that the conductor units act to superheat such gaseous fuel and also the air passing through the conductor into contact with the fuel.

The invention has for an object to provide a novel and improved construction of fuel burner comprising a fire box having a chamber at its lower portion into which the fuel is introduced and a conductor extending to such chamber and having an air inlet through the base of the fire box to secure an admixture of the air and fuel at a point above the bottom of the box.

A further object of the invention is to provide a construction of fire box having a liquid fuel chamber at its base in connection with an upright conductor provided with an air intake communicating with the fire box at a point above the fuel chamber.

Another object of the invention is to provide an improved form of conductor com-

prising a body having a tubular lower portion and discharge openings above the same, together with longitudinal fins extending upward from the base of the conductor so as to conduct heat to the body upon which the conductor is mounted.

Other and further objects and advantages of the invention will be hereinafter set forth and the novel features thereof defined by the appended claims.

In the drawings:—

Figure 1 is a vertical section of the burner;

Figure 2 is a section on line 2—2 of Figure 1;

Figure 3 is a bottom plan;

Figure 4 is a section of parts in elevation of a modified arrangement of the burner;

Figure 5 is an elevation of the conductor; and

Figure 6 is a vertical longitudinal section thereof.

Like reference characters designate corresponding parts throughout the several figures of the drawing.

The invention is adapted for application to any desired construction or configuration of fire box and the number of conductors used in such a box may be varied at will dependent upon the capacity or degree of heat desired to be developed from the burner. In the form shown in Figure 1 the fire box 10 is of substantially rectangular form and the bottom or base 11 thereof provided with a series of air inlet openings 12 adapted to receive the tubular portions 13 of the conductors 14. These conductors comprise vertical standards and are formed with air discharge slots or apertures 15 intermediate their ends.

For the purpose of conveying the heat generated by the flame of the burner to the base of the fire box containing the fuel, each of the conductors is provided with a series of blades or fins 16 extending radially therefrom and terminating at the tubular portion 13 thereof. This portion is also provided with a shoulder 17 resting upon the base 11 of the fire box so that the heat conducted by the blades 16 is conveyed to such body and maintains the same at a high temperature, thus volatilizing the fuel oil contained in the box. The portions 13 of the conductors are of sufficient height to establish the desired fuel level within the fire box and provide for the introduction of the

air through the openings 15 at a point above said level where it will be mixed with the vapor or gas arising from the heated oil. For the purpose of feeding the fuel a conducting pipe 18 extends through the base 11 of the fire box and is provided with a suitable controlling valve 19.

The feed of air to the burner may be controlled and in the form shown in Figure 1 a natural draft is utilized which is supplemented by the heated condition of the conductors which causes the air to rapidly enter the same. Where the burner is used for steam or other heating requiring increased temperature a forced draft may be utilized as shown by the modified form of the invention in Figure 4. In this construction the fire box 20 is formed with a base 21 upon which the conductors 22 are mounted, these being of the construction before described, while the fuel is fed to the lower portion of the box by a pipe 23 and the air conducted to the tubular inlets 24 of the conductors by means of a casing 25 provided with a suitable forced draft device as indicated at 26.

The general operation of the burner will be apparent from the foregoing description from which it will be seen that a level of oil is maintained in the lower portion of the fire box which is highly heated by conduction from the conductors so that as the vapor or gas rises from the oil it is mixed with the heated air passing through the conductor unit so that a combustible fuel mixture is secured at a level above the oil which highly heats the upper solid portion of the conductor and the fins or blades thereof conduct such heat downward to the body of fuel.

While the invention is particularly adapted for use with a low grade fuel oil which may be thus volatilized without incurring the collection of carbon to clog and interfere with the efficient action thereof, still the construction is capable of use in connection with a gaseous fuel such as natural gas which if introduced into the lower portion of the fire box will mix with the air and both being heated form a highly combustible mixture. The fire box may also be of any desired configuration or size dependent upon the heating capacity desired from the burner and the conductors being separate units may be applied in the required number for securing the proper volatilization of the fuel introduced into the box. It will therefore be seen that the invention presents a simple, efficient and economically constructed form of liquid fuel burner designed to efficiently use the cheaper lower grades of fuel oil.

While the details of construction of the fire box and conductor have been specifically shown and described, the invention is

not confined thereto as changes and alterations may be made therein without departing from the spirit of the invention as defined by the appended claims.

Having thus described my invention, what I claim as new and desire to secure by Letters Patent is:

1. A liquid fuel burner comprising a fire box forming a fuel chamber at its lower portion and a body provided with conducting fins extending into said chamber and having an air inlet through the base of the fire box.

2. A liquid fuel burner comprising a fire box forming a fuel chamber at its lower portion and a heat conductor extending into said chamber and having an air inlet through the base of the fire box, said conductor being provided with longitudinal conducting blades extending into said chamber.

3. A liquid fuel burner comprising a fire box forming a fuel chamber at its lower portion and a body provided with conducting fins extending into said chamber and having an air inlet through the base of the fire box, said body having air discharge openings disposed above the liquid fuel level within said chamber.

4. A liquid fuel burner comprising a fire box having an apertured base, a heat conductor disposed therein with a tubular portion located in said aperture and extending upward from said base, and radiating conducting blades extending from said tubular portion to the upper part of the conductor.

5. A liquid fuel burner comprising a fire box having an apertured base, a heat conductor disposed therein with a tubular portion located in said aperture and extending upward from said base and radiating conducting blades extending from said tubular portion to the upper part of the conductor, said conductor being provided with air discharge openings disposed intermediate of said blades and above said tubular portion.

6. A fuel burner comprising an enclosed fire box having an apertured base, a body having heat conducting fins mounted in said box and provided with a base to establish a fuel level and an air inlet opening therein extending through said aperture, and means for feeding and controlling the flow of fuel to said fire box.

7. A fuel burner comprising an enclosed fire box having an apertured base, a body having heat conducting fins mounted in said box and provided with a base to establish a fuel level and an air inlet opening therein extending through said aperture, means for feeding and controlling the flow of fuel to said fire box, and means for effecting a forced draft of air through said body.

8. A liquid fuel burner comprising an

5 enclosed fire box having a plurality of apertures through the base thereof, and a plurality of heat conducting standards each having a tubular base seated upon said apertures to form an air intake and provided with discharge openings above said base disposed intermediate a plurality of conducting fins.

10 9. A heat conductor for fuel burners comprising a body having a tubular base and longitudinally disposed discharge slots communicating therewith and disposed intermediate a plurality of conducting fins ex-

tending between said base and the upper solid portion of the body. 15

10 A heat conductor for fuel burners comprising a body having a tubular base and discharge slots communicating therewith and disposed between said base and the upper solid portion of the body, said body being formed with radially disposed fins connecting the base and upper portions. 20

In testimony whereof I affix my signature.

WILLIAM PAUL RUDKIN.
